CLAIM

The ornamental design for a coolant reservoir for attachment to machine tools, as shown.

DESCRIPTION

FIG. 1 is a top plan view of the coolant reservoir for attachment to machine tools showing the new design.

FIG. 2 is a front elevational view thereof.

FIG. 3 is an end elevational view of the reservoir from the left side as viewed in FIGS. 1 and 2.

FIG. 4 is an end elevational view of the reservoir from the right side as viewed in FIGS. 1 and 2.
